PAINT SPRAYING APPARATUS

Solomon Metrick and Jacob J. Rosen,
Brooklyn, N. Y.

Application March 7, 1939, Serial No. 260,272

2 Claims. (Cl. 299—140)

This invention relates to an apparatus for therewith spraying paint or other materials, such as lacquer or enamel, for applying a coating of the material upon any required surfaces.

The principal object of the invention is to provide an apparatus for the above purpose which will be simplified, efficient, strong, durable, conveniently and economically manufacturable, and improved.

Heretofore, the operation of apparatuses of this type at times entailed dangers produced by inadvertently overloading the paint containing receptacle thereof with too great an air pressure, which sometimes resulted in explosion. It is therefore a further object of the invention to remedy the aforesaid disadvantage, and to provide an apparatus possessed of inherent means which will obviate possibility of such danger and which will be furthermore conveniently and efficiently operable.

A still further object of the invention is to provide an apparatus for the above purpose, which will compel the operative to stand by it during the loading of its paint containing receptacle with air pressure, but in which the feed of air pressure will automatically cease upon the operative leaving the apparatus.

A still further object is to provide an apparatus for the above purpose, the requisite working parts of which will be maintained as a unit, for ready and convenient attachment thereof interchangeably to any one of a plurality of paint containing receptacles.

Other objects and advantages will herein-after appear.

In the accompanying drawings—

Fig. 1 shows a plan view of the paint spraying and applying apparatus of the invention.

Fig. 2 is a side elevation of the apparatus shown in Fig. 1.

Fig. 3 is a front elevation of the paint spraying apparatus, illustrating a cross-section thereof, taken on the line 3—3 of Fig. 1.

The apparatus 1 is equipped with an upright cylindrical tank 2, serving as a receptacle for the compound liquid 3 which may consist of paint, lacquer, or enamel, or any other coating material. In the roof-wall 4 of the tank 2 is provided a tapped opening 5, in which is threaded the upper terminal of a siphoning pipe 6 that extends to the bottom of said tank. A nipple 7 threads into the pipe 6, and the joint thereto is sealed by a nut and gasket 8 threaded about said nipple and against the tank-wall 4, and a union 9 joins the nipple 7 with a nipple

10 threaded to a cross 11 carrying a coupling 12 to which is attached a hose 13 leading to a usual spraying gun 14. To cross 11 is connected a valve 15 to which is in turn joined a T-fitting 16 provided with a coupling 17 for a hose 18 leading to the gun 14, and said fitting carries another coupling 19 for a hose 20 leading to a compressed air source 21. In the tank-wall 4 is formed an opening 22 tapped to receive a nipple 23 which is secured and sealed in place to said wall by a nut and gasket 24, and to said nipple is joined a union 25 connected to a cross 26 carrying an elbow 27 to which is connected a pressure gauge 28. To the cross 26 is connected a valve 29 having a nozzle 30. The valves 15, 29 are operable by lever handles 31, 32 respectively, to both of which is pivotally joined, as shown in Fig. 1, a link 33 configurated as a handle 34, whereby both of said lever handles may be manipulated by actuation by the single handle 34 common to both of them. Thus, operating the link 33 to dispose the handles 31, 32 to a vertical position, as viewed by the dash and dot lines, Fig. 1, simultaneously closes the valves 15, 29, while similarly returning said handles to a horizontal position opens both of the valves.

To each of the crosses 11, 26 is connected an elbow 35 which are in turn connected by a rod 36, Fig. 1, and said crosses are also connected by bars 37, 38, in which manner all of the depending parts connected to the tapped opening 22 of tank-wall 4 and all of the depending parts connected to the opening 5 are bridged together by said rod and bars and are rigidly secured to constitute a unit, which may be therefore interchangeably connected to any one of a plurality of paint containing tanks 2, by merely threading in of the nipples 7, 23, and nuts 8, 24, as illustrated in Fig. 3.

In the utilization and operation of the apparatus, the aforesaid unit constituting it is secured to a paint containing tank 2, and the hose lines 13, 18, 20 are coupled to the apparatus as shown in Fig. 1. The valves 15, 29 are then opened simultaneously by the operative's one hand manipulating the link-handle 34. Thereupon, compressed air flows from source 21 through hose 20, fitting 16, valve 15, cross 11, and through union 9, nipple 7, and into pipe 6, from the lower terminal of which it is injected into the painting fluid, as illustrated in Fig. 2, in which manner the fluid becomes agitated and thoroughly admixed of all its constituent substances, as required for the spraying process. The air passing through the liquid

3 thereupon fills the space 38 thereabove and is exhausted through nipple 23, union 25, and the valve 29. This manner of circuiting the air through the liquid 3 in conjunction with its said exhaustion is conducive to most efficient intermixing of the substances comprising the liquid. In practice, the operative continues his hold upon link handle 34 during the mixing of the liquid, upon completion of which he applies the thumb 10 of his other hand against the opening of valve-nozzle 30 and thereby closes it. Thereupon the compressed air emanating from the liquid 3 remains in space 38 thereabove and raises the pressure in the tank, as becomes observable by 15 the gauge 28. As soon as the tank pressure reaches a required amount, the operative swings back the link handle 34 and thereby simultaneously closes both of the valves 15, 29. The painting liquid 3 is then siphoned through tube 20 6, union 9, cross 11, and from the latter through hose 13 to the spraying gun 14.

It will be noted that in the operation of this apparatus, any attempted feeding of compressed air into the tank 2 automatically opens the 25 exhausting valve 29 and thereby prevents formation of pressure within the tank until the operative deliberately closes the nozzle 30 with his finger, that while performing the latter his eye is directed upon the gauge 28 to ascertain the required pressure produced within the tank, and that the subsequent simultaneous closing of 30 both valves 15, 29 with the single handle 34 shuts off the incoming compressed air completely, from which it will be evident that any danger 35 of formation of excessive pressure within the tank is obviated. Should the pressure become low within the tank, the same may be replenished readily by similarly operating the handle 34 and

applying the finger to nozzle 30, to remix the fluid and restore the pressure. A safety valve 4a connected to the tank 2 in its roof 4 serves at all times to prevent development of undue air pressure within the tank over its prescribed capacity. 5

Variations may be resorted to within the scope of the invention, and portions of the improvements may be used without others.

Having thus described our invention, we claim: 10

1. A paint spraying apparatus having the combination of a closed receptacle for the painting liquid, a pipe leading from the upper part of said receptacle into the liquid, a pipe leading from said first pipe for connection to a compressed air source, a pipe leading from said receptacle for connection to a paint spraying gun, a valve in said second pipe for admitting and shutting off the air from said source, an air exhausting pipe leading from the upper part of said receptacle, a 15 valve in said exhausting pipe, and a link joining both of said valves for simultaneous and interdependent operation of both of said valves.

2. A paint spraying apparatus having the combination of a closed receptacle for the painting liquid, a pipe leading from the upper part of said receptacle into the liquid, a pipe leading from said first pipe for connection to a compressed air source, a pipe leading from said receptacle for connection to a paint spraying gun, a valve in 20 said second pipe for admitting and shutting off the air from said source, an air exhausting pipe leading from the upper part of said receptacle, a valve in said exhausting pipe, and means joining both of said valves for simultaneous and interdependent operation of both of said valves. 35
